UNITED STATES PATENT OFFICE.

JOHN E. FRENCH AND ORRIN A. FRENCH, OF ST. CLOUD, MINNESOTA.

AUTOMATIC GRAIN-BUNDLE SHOCKER.

SPECIFICATION forming part of Letters Patent No. 626,653, dated June 6, 1899.

Application filed August 25, 1896. Serial No. 603,836. (No model.)

To all whom it may concern:

Be it known that we, JOHN E. FRENCH and ORRIN A. FRENCH, citizens of the United States, residing at St. Cloud, in the county of Stearns, State of Minnesota, have invented certain new and useful Improvements in Automatic Grain-Bundle Shockers, of which the following is a specification, reference being had therein to the accompanying drawings.

The objects of our invention are to provide a machine of simple and comparatively inexpensive construction to take automatically the bound bundles of grain from a self-binding grain-harvester, pack them in the form of a shock into a horizontally-retained conical receiver connected to the side of said grain-binder, tilt the receiver, and deposit said shock upon the ground in a vertical position, after which automatically to turn the receiver over said shock and return it into a position to receive the bundles for another shock. We attain these objects by the construction illustrated in the accompanying drawings, in which—

Figure 1 is a rear elevation, with the sheet metal grain-receptacle removed, of a machine constructed in accordance with our invention, one side of which is shown adjustably attached to the frame of a grain-binding harvester.

Fig. 1^a is a perspective view of one of the guides for the reciprocating bars U. Fig. 2 is a plan view of the same. Fig. 3 is a side elevation of the inner or right-hand side of the machine disconnected from the harvester.

Fig. 4 is a side elevation of the outer or left-hand side of the machine. Fig. 5 is a front elevation of the machine. Fig. 6 is a plan view, on a small scale, of the adjustable rods connecting the shocker-frame to the grain-binder frame. Fig. 7 is a side elevation of the machine, showing the bundle-receptacle in a vertical position to discharge the bundles.

Fig. 8 is a plan view, on a large scale, of a portion of the machine, showing parts of the gearing and one of the clutches and its operating-wedge. Fig. 9 is a rear view of one of the clutches and its operating-wedge.

Similar letters refer to similar parts throughout the several views.

In said drawings, B represents the two sides of the frame, that are connected together at the front end of the machine by braces B²,

thereby constituting a substantially U-shaped frame open at the rear. Said frame is carried by wheels A² on the sides and a caster-wheel A at the front, the spindle G of the forked caster-frame being received in perforations or bearings made in the front braces B² of the frame B. On top of each side frame B are secured two batter-posts C, having their upper ends united in pairs by bars C², that are united at the front by bars B², forming therewith also a U-shaped frame. In said bars C², toward the rear end thereof, are secured journal-boxes receiving trunnion-shafts P. The inner ends of each shaft P is provided with a crank-arm P², Fig. 2, to the under-side of which are attached the ends of inverted arch-ribs d, Figs. 1, 3, and 4, forming arcs of different diameters to constitute the support for a truncated conical receptacle D, preferably of sheet metal corrugated with transverse ribs d². To the top of the outer crank-arm P² are also secured two arched rods d', the free ends of which extend to points nearly over the inner crank-arm P² and are provided with elastic looped ends d³, their elasticity being to facilitate the entrance of the bundles and still maintain a support for said bundles while the receptacle is revolved. Hinged also to the top of the outer crank-arm P², between the arched rods d', there is a partly arched pressure-arm e, on top of which is attached, directly over the axis of the grain-receptacle, a vertical screw-rod e⁴, that passes through a cross-tie e⁵, the ends of which are bent down and encircle the arched rods d'. The cross-tie e⁵ is adjustably retained between the end of a spring i, coiled upon the screw-rod e⁴, and a thumb-nut e⁶ on the outer end of said screw-rod.

To temporarily clasp together the grain tops of the grain bundles within the receptacle D while the latter is turned over to cause them to be discharged with their butts spread apart, but substantially in a standing position upon the ground, the smallest pair of inverted arch-ribs d⁴ operate as clamping-arms and have their outer ends pivoted on a shaft p' to the lower ends of lugs p² pendent from the crank-arms P² substantially directly under the axis of the trunnion-shafts P and are hinged together at d⁷ in the lower portion of their arch. To cause said smallest pair of

ribs d^4 to be pressed upwardly toward the axis of the receptacle D at the proper time, there is pivoted to the left-hand lug p^2 , Fig. 1, a lever e^2 , the lower end of which carries a roller to bear upon the underside of the small rib d^4 . The upper end of the lever e^2 is at the proper time pressed upon by one branch of a yoke j , that passes vertically through the crank-arm P^2 . The yoke j constitutes a pressure device that is kept elevated by a coil-spring wound around one of its legs, while the other branch carries a friction-roller j^2 , by which it is depressed when said roller passes within an eccentric concave guide j^3 , projecting up from the outer top bar C^2 of the frame. To steady the receptacle D in its rotation and arrest said receptacle when it has reached a position suitable to receive the grain bundles, there is secured to the two longest inverted arch-ribs d in the lower portion thereof an arm d^6 , carrying a roller d^7 , that is received within the bend of a spring-hook e^3 , Fig. 4, secured to the lower portion of a butting-board E. To render the hook e^3 springy, it is made of flat spring metal secured from its upper end only to said board E. The above-described parts are constituents of the conical receptacle D.

To start and arrest at the proper time the revolution of the receptacle D by operating upon the clutch mounted upon the shaft of the left-hand ground-wheel A^2 , there is mounted upon the left-hand trunnion-shaft P an eccentric H, the strap and rod H^2 of which carries on its lower end a wedge m , adapted to be forced between a roller n' , mounted in stationary bearings upon the frame B, and a roller n , carried on the upper ends of the jaws of a ring-lever R, Figs. 1, 5, 8, and 9, having pins entering an annular groove in the sliding member K of the clutch placed upon the axle of the ground-wheel A^2 on the left-hand side of the machine.

The lower end of the lever R is pivoted to one end of a metal strap r , that has its opposite end pivoted to the bottom of the inner bearing of the axle of the ground-wheel A^2 . A coiled spring S is placed upon said shaft between said bearing and the member K of the clutch to normally force it in engagement with the second member of the clutch carried by the hub of the left-hand wheel A^2 . The member K of the clutch carries also a sprocket-wheel I, that is connected, by means of a sprocket-chain I^2 , with a sprocket-wheel I^3 on the outer end of the trunnion-shaft P and gives at the proper time one revolution to the said shaft.

To the two sides of the bottom frame B is pivoted the butting-board E, placed between them, said board having projecting from each of its two lower corners a spindle p , that is received in bearings upon said frame. Said board E is normally retained in a nearly-vertical position by means of a coiled spring E^2 on each side, set in an inclined position. The upper end of each spring is secured to the

edge of the board E about one-third of its height and has its lower end secured to the frame B at a short distance from the axle-bearing of the rear ground-wheels.

To prevent the butting-board from returning too suddenly to a vertical position after the shock of grain bundles has been discharged, cushion-springs C^4 , Fig. 4, are secured to the bars C^2 of the frame, along the inner side thereof, in the path of the butting-board. Vertically in the center of the inner face of the butting-board is secured thereto a recessed iron bar E^3 , that constitutes a track for the roller d^7 on the lower edge of the receptacle D. The roller d^7 is arrested at the lower end of its course by the projecting part of the spring-hook e^3 , as before stated. The butting-board is shown in Fig. 7 in full lines in its normal position and also tilted forward in dotted lines when the receptacle D is released to discharge its shock.

To secure the grain-shocker to a grain-binder frame B F (partly shown in Fig. 1) in a strong but adjustable and flexible manner to accommodate the parts to uneven ground, two rods parallel to each other and a rod placed diagonally between them are used. Each rod consists of a bar Q, having one end pivoted at q to the binder-frame in such manner that said bar can oscillate vertically, and a tubular sleeve Q^2 to receive in one end the opposite end of the bar Q. The opposite end of the sleeve Q^2 is hinged to the shocker-frame at q^2 in such a manner that its tubular end can oscillate horizontally, and a thumb-screw q^3 in engagement with the side of the sleeve Q^2 has its point bearing upon the bar Q. The flexible arrangement of the hinges at the ends of the rods may be reversed, if desired. The diagonal brace Q^3 is also made of two lengths adjustable relatively to each other and has its ends hinged to the binder-frame and shocker-frame, as described for the compound rods Q Q².

To advance the grain bundles from the grain-binder table into the bundle-receiver D, three or more conveyer-bars U, having ratchet-teeth on their top face, are used. They receive adjacent to their outer ends the cranks of a crank-shaft V, that is carried in suitable bearings in two parallel bars C^5 , Fig. 2, that are hinged to forked lugs c^2 , projecting from the side of the top bar C^2 of the frame. The outer ends of the bars C^5 are adjustably supported by rods c^3 , having one end hinged thereto and the opposite end received in a sleeve c^4 , having its lower end pivoted to a lug projecting up from the frame B. The stubbleward portion of each conveyer-bar U has a slot u in its side to receive the hooked fingers on the upper ends of the arms of guiding-staples u^2 , that are pivoted to lugs u^3 , Figs. 1, 2, and 3, secured to the bars C^2 of the frame, the fingers of the staples constituting guides for the front portion of the conveyer-bars.

To support the grain bundles above the

conveyer-bars U while the latter are reciprocated grainward before causing a new advance of said bundles, three or more rods C⁶ have their rear end secured between the bars 5 C⁵ to a bar uniting said bars C⁵ together under the binder-table, while their front end extends over the frame C close to the entrance to the receiver D. At a suitable height above the conveyer-bars U and the rods C⁶ 10 and substantially parallel to the latter are placed a series of rods C⁷ to prevent the grain bundles from being crowded upward. The rods C⁷ are carried by rods C⁸, united in pairs, said rods C⁸ having their lower ends 15 forked and adjustably secured to the bars C⁵.

To rotate the crank-shaft V, a sprocket-wheel is mounted on its front end, to which motion is given as follows, reference being had particularly to Fig. 8: The member K⁶ 20 of the clutch on the axle of the right-hand wheel A² carries a sprocket-wheel i², that is connected by means of a chain i² with a sprocket-wheel i³, mounted on a counter-shaft p³, located in advance of the wheel A². On 25 the innermost end of the shaft p³ is mounted a miter-gear L, that meshes with a miter-gear L², mounted upon a shaft p⁴ at right angles to the shaft p³. Upon the shaft p⁴, toward its front end, is mounted a sprocket-wheel i⁴, that is connected by means of a chain i⁵, with a sprocket-wheel i⁶ upon the front end 30 of the crank-shaft V, Fig. 1.

To guide the butts of the grain bundles toward the inner face of the butting-board E, 35 a guide-board T is secured to the front face of the front bar C⁵ to constitute a slightly flaring entrance toward said butting-board E.

To automatically release the receptacle D from engagement with the spring-hook e³, 40 carried by the butting-board, and permit said receiver to be tilted in a vertical position to discharge the shock and thence to be turned over, the means employed are particularly shown in Figs. 4 and 5, in the latter of which 45 the pressure-arm e is shown in dotted lines in two positions. It is hinged, as previously stated, on top of the outer crank-arm P². The outer end of the arm e, adjacent to its pivot, is provided with a convex eccentric 50 heel that bears against the convex arm of a Z-shaped lever t, the middle portion of which is pivoted on top of the crank-arm P². The lower arm of the lever t is pivotally connected, by means of a diagonally-located connecting-rod t², with a short standard t³, Fig. 5, that has its lower end pivoted upon the front portion of the frame B, and said standard is connected, by means of a chain t⁴, with the hook e³ on the butting-board E. To permit the driver to discharge the bundle-receiver at any time whatever may be the number of bundles therein, a cord t⁵ has one end attached to the upper end of the hinged standard t³, and the opposite end is within easy 65 reach of said driver.

To start and stop the grain-bundle-feeding conveyers U, the outer end of the trunnion-

shaft P on the right-hand side of the machine is provided with an eccentric H⁵, having a strap and eccentric-rod H⁶ and a wedge m on the lower end of said rod. Said wedge enters 70 between the rollers n and n' to throw the movable member K⁶ out of clutch, but is lifted by the eccentric H⁵ when said member K⁶ is to be again in clutch with the other member or the 75 hub of the wheel A².

In operation, the bundle-packer having the adjustable rods c³ c⁴, the said rods permit it to be set to any elevation of the grain-binder. The ejector-arm E A of the binder crowds the 80 grain bundles under the guide-rods C⁷ onto the reciprocating toothed conveyers U, which advance them into the conical receptacle D. This action continues until sufficient bundles have accumulated therein to raise the pressure-arm e and force it against its top spring i until the convex eccentric heel on its lower end has acted through the lever t, connecting-rod t², hinged standard t³, and chain t⁴ to pull the hook e³ from under the roller d⁷ at the 90 lower end of the receptacle D. Said conical receptacle D, being pivoted from its top edge through the medium of the crank-arms P² and trunnion-shafts P in the rear of its small end, is tilted by the weight of the inclosed shock 95 to a vertical position, as shown in Fig. 7. The shock is thus dropped, standing with the butts of the bundles resting upon the ground.

In the operation of the machine after the receptacle D has been filled with grain bundles and while said receptacle is revolved and discharged five distinct movements occur in the mechanism. First, the pressure-yoke j is depressed while its roller j² passes under the concave guide j³ and the roller on the side of 100 the lower portion of its inner leg presses upon the upper end of the lever e². The roller on the lower end of said lever e² bears against the convex edge of the rib d⁴ and the latter becomes contracted around the tops of the 105 grain bundles, squeezing and holding them until they are dropped upon the ground with a wider spread at the bottom. As soon as the roller j² of the yoke j passes from under the concave guide j³ the coiled spring on the leg 110 of the yoke expands and causes said yoke to assume its original elevated position. Second, the butting-board E is tilted forward, as shown in Fig. 7, through the medium of the lever t, the connecting-rod t², hinged standard t³, and chain t⁴, releasing the receptacle 115 D from engagement with its supporting-hook e³. Third, the eccentric H on the left-hand trunnion-shaft P, its strap and rod H⁶, draws the wedge m on its lower end sufficiently up 120 to allow the member K of the clutch under the impulse of the spring S to engage with the second member of the clutch, that is secured to the side of the hub of the left-hand drive-wheel A². Said drive-wheel being in motion 125 immediately causes the sprocket-wheel I, through the medium of the chain I², to revolve the sprocket-wheel I³ and the latter the trunnion-shaft P, upon which it is mounted. Said 130

shaft P, being one of the trunnions of the receptacle D, revolves the latter and causes it to be turned over. During the last part of the revolution of the receptacle D its roller d⁷ comes in contact with the iron track E³ on the butting-board and follows it down to the arresting-hook e⁸. When it has reached this point, the eccentric H and its rod H² force the wedge m on the lower end of said rod between the rollers n and n' and throw the member K of the clutch out of mesh with the member on the drive-wheel A² and stop that part of the mechanism, with the receptacle D in a horizontal position to receive grain bundles. Fourth, the eccentric H⁵ on the end of the right-hand trunnion-shaft P, which is provided with a strap and eccentric-rod H⁶ and a wedge m on the lower end of said rod. Said wedge enters between the rollers n n' and throws the inner member of the clutch K⁶ out of mesh with the outer member, which is secured to the hub of the driving-wheel A². This action immediately stops the bundle-feeding conveyors U, and thereby allows the conical receptacle D to be discharged and turned over without interference. It also permits any bundle coming from the binder to lie on the rods C⁶ of the conveyer. Fifth, at the moment that the receptacle D arrives at a horizontal position and the locking-hook e³ receives the roller d⁷ of said receptacle the eccentric H⁵ on the right-hand trunnion-shaft draws up the wedge m and allows the clutch member K⁶ to close by the action of the coil-spring S into engagement with the clutch member on the drive-wheel A², immediately starting the bundle-packer into action.

Before filling the receptacle the spring p⁶, coiled upon the shaft p' of the clamping-ribs d⁴, having one end bearing upon the lower half of the lever e², retracts the latter from contact with said clamping-rib d⁴ and leaves unobstructed the entrance to the receptacle.

Having now fully described our invention, we claim—

1. In an automatic grain-bundle shocker, the combination of the frame of a grain-binder, a bundle-shocker frame hinged to, and adjustably secured to the side of the grain-binder frame, wheels carrying the shocker-frame, a U-shaped frame in a horizontal plane above the top of the carrying-wheels and a semiconical receptacle adapted to be turned over around horizontal trunnions pivoted to the side of the U-shaped shocker-frame substantially as described.

2. In an automatically-operated grain-bundle shocker, the combination of the frame of a grain-binder, a U-shaped bundle-shocker frame hinged thereto, wheels carrying said shocker-frame, posts upon said frame, and a secondary U-shaped frame upon said posts, with a semiconical receptacle pivoted to the inner sides of the secondary frame and adapted to be turned over substantially as described.

3. In an automatic grain-bundle shocker,

the combination of the frame of a grain-binder, a U-shaped bundle-shocker frame hinged thereto, wheels carrying said frame, 70 posts upon said frame, and a secondary U-shaped frame upon said posts with a semiconical receptacle pivoted to the inner sides of the secondary frame, and arched rods over said receptacle and means to turn over said 75 receptacle substantially as described.

4. In an automatic grain-bundle shocker, the combination of the frame of a grain-binder, a U-shaped bundle-shocker frame hinged thereto, wheels carrying said frame, 80 posts upon said frame, and a secondary U-shaped frame upon said posts, trunnion-shafts passing through the secondary frame, crank-arms secured to the inner ends of said shafts, inverted arch-rods secured to the 85 crank-arms, a roller-carrying arm d⁶ secured to said arch-rods and a semiconical receptacle upon said arch-rods substantially as described.

5. The combination of a U-shaped bundle-shocker frame having its sides united together at the front end, wheels carrying said frame, posts upon said frame, and a secondary U-shaped frame, upon said posts, trunnion-shafts passing through the secondary 95 frame crank-arms secured to the inner ends of said shafts, a semiconical receptacle carried by said crank-arms, lugs p² pendent from the crank-arms and a pair of ribs d⁴ having one end hinged to the lugs p² and devices for causing the free ends of the ribs to approach each other by the tilting of said receptacle and arched rods d' and e substantially as described.

6. The combination of a U-shaped bundle-shocker frame having its sides united together at the front end, wheels carrying said frame, posts upon said frame, and a secondary U-shaped frame upon said posts, trunnion-shafts on the secondary frame, crank-arms secured to the inner ends of each shaft, a semiconical receptacle carried by said crank-arms, lugs p² pendent from the crank-arms, arched rods d' and e a pair of curved ribs d⁴ pivoted together between their ends 115 and each having one end hinged to the lugs p² and a lever e² adapted to press against the convex side of one of the ribs d⁴ and devices for operating the lever by the tilting of the said receptacle substantially as described.

7. The combination of a U-shaped bundle-shocker frame, trunnion-shafts thereon, crank-arms secured to the inner ends of said shafts, a semiconical receptacle carried by said crank-arms, lugs p² pendent from the 125 crank-arms, a pair of curved ribs d⁴ pivoted together between their ends and each having one end hinged to the lugs p² a lever e² adapted to press against the convex side of one of the ribs d⁴, a yoke j having one of its branches 130 bearing upon the lever e², and a stationary concave guide j³ in the path of said yoke substantially as described.

8. The combination of a U-shaped bundle-

shocker frame, trunnion - shafts mounted thereon, crank-arms secured to the inner ends of said shafts, a conical receptacle carried by said crank-arms, two arched rods d' having one end secured to one of the crank-arms and the opposite end provided with elastic loops substantially as described.

9. The combination of a **U**-shaped bundle-shocker frame, a butting-board hinged there-
10 to trunnion-shafts mounted upon said frame, crank-arms secured to the inner ends of said shafts, a conical receptacle carried by said crank-arms, two arched rods d' having one end secured to one of the crank-arms, a pres-
15 sure-arm e , hinged to said crank-arms be-
tween the rods d' and having its free end yieldingly supported by said rods d' and the
20 **Z**-shaped lever t and its connections with the butting-board substantially as described.

20 10. The combination of a **U**-shaped bundle-shocker frame, trunnion - shafts mounted thereon, crank-arms secured to the inner ends of said shafts, a conical receptacle carried by said crank-arms and having a roller
25 d' projecting from its lowest end, a butting-
board E hinged to the shocker-frame and a
hook e^3 secured to the butting-board to re-
ceive the roller d' substantially as described.

11. In an automatic grain-bundle shocker,
30 the combination of the frame of a grain-
binder, a **U**-shaped bundle-shocker frame
hinged to the grain-binder, trunnion-shafts
mounted upon the shocker-frame, crank-arms
secured to the inner ends of said shafts, a
35 conical receptacle carried by said crank-arms
and adapted to be turned over said shafts to
discharge it, and be returned into position to
be loaded, arched rods d' secured to one of
40 the crank-arms over the receptacle, and means
to automatically release the conical recepta-
cle substantially as described.

12. The combination of a **U**-shaped bundle-
shocker frame, trunnion - shafts mounted
thereon, crank-arms secured to the inner
45 ends of each shaft a conical receptacle car-
ried by said crank-arms and having a roller
 d' , a butting-board E a hook e^3 , projecting
from the rear of the butting-board, a pivoted
pressure-arm e having a laterally-projecting
50 heel, a double crank-lever t , having one end
bearing against said heel and means substan-
tially as described to connect said crank-lever
with the hook e^3 to release the conical recep-
tacle.

55 13. The combination of a **U**-shaped bundle-
shocker frame, trunnion - shafts mounted
thereon, crank-arms secured to the inner
ends of said shafts, a conical receptacle car-
ried by said crank-arms and having a roller
60 d' projecting from its lower end, a butting-
board E hinged to the shocker-frame the hook
 e^3 on said butting-board and springs E^2 hav-
ing one end secured to the sides of the but-
ting-board and the other end to the shocker-
65 frame substantially as described.

14. The combination of a **U**-shaped bundle-

shocker frame, supporting-wheels on the sides thereof, trunnion - shafts mounted on said frame, crank-arms secured to the inner ends of said shafts, a conical receptacle carried by
70 said crank-arms, a sprocket-wheel mounted upon the stubbleward trunnion - shaft, the supporting-wheel A^2 , its sprocket-wheel and chain, two members of a clutch upon the axle of said supporting-wheel, one of said mem-
75 bers being actuated by a spring, a wedge m in engagement with said member, an eccentric H upon said stubbleward trunnion-shaft substantially as described.

15. The combination of a **U**-shaped bun-
dle-shocker frame, supporting-wheels on the sides thereof, trunnion-shafts mounted on said frame, crank-arms secured to the inner ends of said shafts, and a conical receptacle car-
ried by said crank-arms, a sprocket-wheel I^3
85 on one of the trunnion-shafts, the two mem-
bers of a clutch on the axle of one of the sup-
porting-wheels, the wedge m adapted to op-
erate on the movable member of the clutch,
and an eccentric to operate said wedge from
90 the trunnion-shaft of the receptacle in con-
nection with a chain and sprocket-wheels I ,
 I^3 substantially as described.

16. The combination of a **U**-shaped bun-
dle-shocker frame, supporting-wheels on the
95 sides thereof, trunnion-shafts mounted on said
frame, crank-arms secured to the inner ends of
said shafts, and a conical receptacle car-
ried by said crank-arms, with the eccentric
 H on one of the trunnion-shafts, the eccen-
100 tric-rod and a wedge m on the lower end of
said rod, said wedge being between a roller
mounted on the shocker-frame and a roller
mounted upon a member of a clutch upon the
axle of one of the supporting-wheels, and a
105 gear connection between the clutch and the
trunnion of the receptacle substantially as
described.

17. The combination of a **U**-shaped bun-
dle-shocker frame, supporting-wheels on the
110 sides thereof, trunnion - shafts mounted on
said frame, crank-arms secured to the inner
ends of said shafts, a conical receptacle car-
ried by said crank-arms, the eccentric H^5
upon the grainward trunnion-shaft, the ec-
115 centric-rod H^6 and a wedge on the lower end
of said rod, the grainward supporting-wheel,
two members of a clutch on the axle of said
wheel, one of said members being actuated
by a spring in one direction and by the wedge
120 in the opposite direction, the sliding member
carrying a sprocket-wheel, the bundle-con-
veyer and chain to operate a bundle-conveyer
substantially as described.

18. The combination of a **U**-shaped bun-
dle-shocker frame, supporting-wheels on the
125 sides thereof, trunnion - shafts mounted on
said frame, crank-arms secured to the inner
ends of said shafts, a conical receptacle car-
ried by the crank-arms, two members of a
130 clutch on the axle of the grainward support-
ing-wheel, a sprocket-wheel upon one of said

members, another sprocket-wheel in advance thereof, miter-gears L and L^2 , sprocket-wheels i^4 , i^6 and their connecting-chain, with the bundle-feeding mechanism consisting of the 5 toothed conveyer-bars U having slots in their two sides and double-hooked retainers u^2 in engagement with said slots, and a crank-shaft journaled in the frame and its cranks journaled in the rear end of said conveyer-bars 10 substantially as described.

19. The combination of a bundle-shocker frame, supporting-wheels on the sides thereof, trunnion-shafts mounted on said frame, crank-arms secured to the inner ends of said 15 shafts and a conical receptacle carried by the crank-arms with a bundle-feeding mechanism consisting of the parallel bars C^5 having their inner ends pivoted to the shocker-frame, the adjustable rods c^3 , c^4 , supporting the outer 20 ends of the bars C^5 the feed-bars U , the crank-shaft V , the sprocket-wheel i^6 thereon, the chain i^5 , sprocket-wheel i^4 , its shaft, the bevel-gears L and L^2 , the chain i^2 , and sprocket-

wheel on the axle of the supporting-wheels, substantially as described. 25

20. The combination of a bundle-shocker frame, supporting-wheels, trunnion-shafts mounted on said frame, crank-arms secured to the inner ends of said shafts, and a conical receptacle carried by the crank-arms with a bundle-feeding mechanism consisting of the parallel bars C^5 , having their inner ends pivoted to the shocker-frame, the shaft V , having cranks thereon, the conveyer-bars U , the rods C^6 , between said conveyer-bars, the rods C^7 , above them, the adjustable rods C^8 , carrying the rods C^7 , and the guide-board T , in front of said rods, substantially as described. 30 35

In testimony whereof we hereunto affix our signatures in presence of two witnesses.

JOHN E. FRENCH.
ORRIN A. FRENCH.
